UNITED STATES PATENT OFFICE.

FRANK FILA, OF NEW YORK, N. Y.

DESIGN FOR A LAMP STAND.

Application filed May 15, 1925. Serial No. 13,459. Term of patent 3½ years.

To all whom it may concern:

Be it known that I, FRANK FILA, a citizen of Austria, residing at New York, N. Y., have invented a new, original, and ornamental Design for Lamp Stand, of which the following is a specification, reference being had to the accompanying drawing, forming part thereof.

The figure is a side elevation of a lamp stand, showing my new design.

I claim:

The ornamental design for a lamp stand, as shown.

FRANK FILA.
